UNITED STATES PATENT OFFICE.

ALFRED B. ZUCKERT, OF EAU CLAIRE, WISCONSIN.

CLEANING MECHANISM.

Application filed May 9, 1921. Serial No. 467,913.

To all whom it may concern:

Be it known that I, ALFRED B. ZUCKERT, a citizen of the United States, and a resident of the city of Eau Claire, in the county of 5 Eau Claire and State of Wisconsin, have invented certain new and useful Improvements in a Cleaning Mechanism; and I do hereby declare that the following is a full, clear, and exact description of the same, reference being had to the accompanying drawings, and to the numerals of reference marked thereon, which form a part of this specification.

This invention relates to a cleaning mechanism, and particularly to a mechanism which is adapted to clean excess cement from rubber clothing and other water-proof goods during the process of manufacture thereof. In the manufacture of rubber 20 clothing adjacent pieces of rubber cloth are joined together by cemented seams and it is desirable that the excess cement be removed before the finished article is used commercially.

25 It is an object therefore of the present invention to provide a cleaning mechanism wherein rotary cleaning members are adapted to remove excess cement and similar material from rubber clothing and other water-30 proof goods.

It is another object of this invention to provide a cleaning mechanism wherein freely rotatable cleaning members are carried by a continuous movable conveyor and 35 moved thereby over a surface to be cleaned.

It is a further object of this invention to provide a portable cleaning mechanism having freely rotatable cleaning members and a power drive for advancing said cleaning 40 members over a surface to be cleaned.

It is also an object of this invention to provide a mechanism for cleaning excess cement from the seams of rubber cloth, said mechanism being adapted to operate without disturbing the remainder of the cloth.

45 It is an important object of this invention to provide an efficient and simple power driven cleaning mechanism which operates to rapidly remove excess material such as cement from the seams of rubber clothing.

Other and further important objects of this invention will be apparent from the disclosures in the drawings and the specification.

55 The invention (in a preferred form) is

illustrated in the drawings and hereinafter more fully described.

On the drawings:

Figure 1 is a view in elevation of a cleaning mechanism embodying the principles of 60 this invention.

Figure 2 is an enlarged fragmentary top plan view of the mechanism with parts in section.

Figure 3 is a section on the line 3—3 of 65 Figure 2 with parts removed.

As shown on the drawings:

The cleaning mechanism of this invention is supported above a working surface 1 by means of a bracket 2 which is secured to 70 said working surface by means of bolts 3. Pivotedly mounted in said bracket 2 is a sleeve 4 which rotatably supports a driving shaft 5 journalled therein in bearings 6 and adapted to be driven from any suitable 75 source of power through a pulley 7 which is secured to one end thereof and which is adapted to have a belt 8 leading to the source of power engaged thereover. Secured to the outer end of the sleeve 4 is an 80 angle bracket 9 which acts to support the cleaning mechanism of this invention. Said mechanism which is driven through a double sprocket 10 secured to the outer end of the shaft 5 will now be described. Abutting 85 the outer face of the angle bracket 9 and secured thereto is a frame plate 11 which is apertured to receive the inner end of the reduced portion of the shaft 5 and a reduced boss 12 on the sprocket 10.

90 Engaged through an aperture in the outer end of the angle bracket 9 and through a registering aperture in the frame plate 11 is a bolt or stub shaft 13 which has rotatably mounted thereon a double pulley 14 which 95 is in alignment with the double sprocket 10. Engaged over each side of the sprocket 10 and the corresponding side of said double pulley 14 is a sprocket chain 15 which acts to rotatably support the cleaning members. 100 Said cleaning members are pivoted on shafts 16 which are integral with connecting pins which connect certain links of the sprocket chains 15 and consequently the cleaning members are independently rotatable between the sprocket chains and 105 adapted to be advanced thereby over a surface to be cleaned. Said cleaning members comprise grooved rollers 17 which are preferably constructed of wood or aluminum 110

and the grooves of which are preferably filled with unvulcanized rubber 18 or a similar material which will act to pick up the excess cement.

5. In order that the chains 15 may be enclosed, a guard plate 19 similar to the frame plate 11 is supported on the outer end of the bolt 13 and on a boss 20 on the double sprocket 10 and is secured in position by 10 means of nuts 21 and 22 secured to the bolt 13 and the outer end of the driving shaft 5 respectively.

The cleaning mechanism is particularly adapted to operate to remove excess cement 15 from a seam 23 which joins together two pieces of rubber or water-proof cloth 24 and 25. Said cloth is laid on the working surface 1 and the cleaning mechanism is normally held away from the seam by means of 20 a coil spring 26 which is engaged between the sleeve 4 and said working surface. It is, of course, apparent that by applying downward pressure to the sleeve 4, said coil spring 26 will be compressed and the cleaning 25 mechanism brought into contact with the seam 23. The rotation of the shaft 5 acts to drive the sprocket 10 to advance the chains 15 and the cleaning rollers 18 are thus advanced along the seam to remove the excess cement therefrom. Due to the fact that 30 these cleaning rollers are independently rotatable, the remainder of the cloth is not disturbed and due to the fact that a plurality of these rollers are continuously in contact with the seam, an efficient and rapid removal of the excess cement or other material is effected.

The mechanism may be manually moved 40 over the cloth, or in cases where heavier and larger cleaning mechanisms are used, the same will act to automatically move the cloth along on the table due to the frictional contact of the advancing rollers therewith.

I am aware that numerous details of construction may be varied through a wide 45 range without departing from the principles of this invention, and I therefore do not purpose limiting the patent granted otherwise than necessitated by the prior art.

50 5. I claim as my invention:

1. A mechanism of the class described comprising a power driven conveyor and independently rotatable soft surfaced cleaning members carried thereby and adapted to make rolling contact with a surface to be cleaned.

55 2. A mechanism of the class described comprising a continuous conveyor and a plurality of separately pivoted soft surfaced

cleaning rollers carried thereby and adapted 60 to make rolling contact with a surface to be cleaned.

3. A mechanism of the class described comprising a frame, a sprocket on the frame, a rotatable means on the frame in alignment with the sprocket, a chain driven by the sprocket and engaged over the rotatable means, and a plurality of rotatable cleaning members having a relatively soft surface carried by the chain and adapted to make 70 rolling contact with a surface to be cleaned.

4. A mechanism of the class described comprising a frame, a sprocket on the frame, rotatable means on the frame in alignment 75 with the sprocket, a chain driven by the sprocket and engaged over the rotatable means, a plurality of freely rotatable cleaning members carried by the chain and adapted to make rolling contact with a surface to be cleaned, and a power drive for 80 the sprocket.

5. A mechanism of the class described comprising a frame, a sprocket on the frame, rotatable means on the frame in alignment with the sprocket, a chain driven by the sprocket and engaged over the rotatable means, and independently rotatable soft surfaced cleaning rollers carried by the chain and adapted to make rolling contact with a 85 surface to be cleaned.

6. A cleaning mechanism for removing excess cement, comprising freely rotatable cleaning members adapted to remove the cement, a conveyor therefor and power driven means connected thereto for advancing the cleaning members.

7. A cleaning mechanism of the class described comprising a driven shaft pivotally mounted above a surface to be cleaned, 100 cleaning means comprising a plurality of rollers supported on the shaft and driven therefrom, and compressible means associated with the shaft for normally holding the cleaning means above the surface to be cleaned.

8. A device of the class described comprising power traversed soft surfaced cleaning means mounted above a surface to be cleaned, and yieldable means for normally holding the cleaning means above the surface to be cleaned.

In testimony whereof I have hereunto subscribed my name in the presence of two subscribing witnesses.

ALFRED B. ZUCKERT.
